UNITED STATES PATENT OFFICE.

WALTER MEADS, OF HIGHTSTOWN, NEW JERSEY, ASSIGNOR TO ACME LACE WORKS, INC., OF HIGHTSTOWN, NEW JERSEY, A CORPORATION OF NEW JERSEY.

DESIGN FOR A LACE MEDALLION.

Application filed February 14, 1928. Serial No. 25,440. Term of patent 3½ years.

To all whom it may concern:

Be it known that I, WALTER MEADS, a citizen of the United States, residing at Hightstown, in the county of Mercer and State of New Jersey, have invented a new, original, and ornamental Design for Lace Medallion, of which the following is a specification, reference being had to the accompanying drawing, forming a part thereof.

The figure is a plan view of the lace medallion, showing my new design.

I claim:

The ornamental design for a lace medallion, as shown.

WALTER MEADS.
